UNITED STATES PATENT OFFICE.

ARMAND SMITH, OF LOS ANGELES, CALIFORNIA.

TOBACCO PIPE.

Application filed February 19, 1924. Serial No. 693,755.

To all whom it may concern:

Be it known that I, ARMAND SMITH, a citizen of the United States, residing at Los Angeles, in the county of Los Angeles and State of California, have invented new and useful Improvements in Tobacco Pipes, of which the following is a specification.

This invention relates to tobacco pipes and it has as one of its objects the provision 10 of means for cooling the bowl and the stem of a pipe.

Another object of this invention is the provision of a pipe which gives a cooler smoke than the pipes heretofore employed.

15 A further object of this invention is the provision of a pipe, the bowl and the stem of which may be cooled by a draft created by the construction of the pipe.

With the foregoing objects in view, together with such other objects and advantages as may subsequently appear, my invention consists in the construction and arrangement of parts hereinafter described and claimed and illustrated in the accompanying drawings, in which:

Figure 1 is a plan view of a pipe embodying my invention,

Fig. 2 is a vertical section taken on the line 2—2 of Fig. 1, and

30 Fig. 3 is a side elevation, partly in central vertical section, of a pipe embodying a modification of my invention.

Referring to the drawings for a more detailed description thereof, and particularly to Figs. 1 and 2, the numeral 5 indicates a bowl having an aperture 6 formed centrally in its bottom 5^a. The bowl 5 is provided with a lateral aperture 7 to the periphery of which is secured a stem portion 8

40 extending at right angles to the bowl 5 and provided at its outer end with female threads 9. The stem portion 8 is also provided with an aperture 8^a. Concentrically positioned within the bowl 5 is a bowl 10 adapted to burn tobacco. The upper edge of the bowl 10 is flush with the upper edge of the bowl 5. The bowl 10 being of smaller diameter and less depth than the bowl 5, a space 11 is formed between the walls of

50 the bowls 5 and 10. The bowl 10 is shown in Figs. 1 and 2 as being held in position by spacing members 12 secured to upper portions of the bowls 5 and 10. The bowls 5 and 10 may be regarded as constituting 55 a single double-walled bowl. The bowl 10 is provided near its bottom with an out-

wardly tapering aperture 14 positioned opposite the aperture in the stem portion 8.

Threadedly engaging the stem portion 8 is a stem portion 15, which at its inner end 60 is tapered to fit the tapered aperture 14 in the bowl 10. A space 16 is thus formed between a portion of the stem 15 and a portion of the stem 8. An end stem portion 18 has a male element 19 which fits into a 65 recess 20 formed in the end of the stem 15. The stem portion 18 is thus removable from the stem 15.

When the pipe is lit, a draft is created 70 which passes through the aperture 6, upwardly through the space 11 and laterally through the space 16 from which it passes through the aperture 8^a. The bowl of the pipe and a portion of the stem are thus cooled by the draft, and a cooler smoke is 75 provided for the smoker.

In the modification shown in Fig. 3, the parts of the pipe are similarly constructed except that the bowl 10 has a threaded shank 10^a formed on its bottom, and this shank 80 engages a threaded recess 5^b formed in the bottom of the bowl 5. The shank 10^a is provided with transverse apertures 10^b which communicates with the space 11 between the bowls 5 and 10. The shank 10^a 85 is also provided with a vertical aperture 10^c, which communicates with the aperture 6 in the bottom of the bowl 5, and also communicates with the apertures 10^b.

While I have herein described one form 90 of my invention, modifications thereof may be devised without departing from the spirit thereof, and it is to be understood that such modifications come within the scope of this invention.

95 What is claimed is:

1. A tobacco pipe comprising in combination an outer bowl, an inner bowl situated therein and having an annular space from the bottom to the top of the inner bowl, a stem connected to the outer bowl, a stem connected to the inner bowl spaced therefrom, and an aperture leading air into the spaces between the bowls and the stems. 100

2. A tobacco pipe having in combination 105 an inner and outer bowl with a space therebetween, a stem connected to the outer bowl, a stem connected to the inner bowl spaced therefrom, an air outlet aperture through the outer stem, and an air inlet aperture 110 leading into the spaces between the bowls and the stems.

3. A tobacco pipe comprising an inner bowl and an outer bowl having an annular space extending from the bottom of the inner bowl to the top of both bowls, stems connected to each bowl with a space therebetween, an aperture through the stem of the outer bowl, an air inlet opening through the base of the outer bowl into the spaces between the bowls and the stems.
- 10 4. A tobacco pipe comprising in combination an outer bowl having a threaded recess in its base, an inner bowl having a shank screw threaded into the recess, said bowls being spaced from each other from the base to the top, an aperture through the base of the outer bowl and the shank of the inner bowl, stems connected to each bowl with a space therebetween, and an air outlet through the stem of the outer bowl.

In testimony whereof I have signed my name to this specification.

ARMAND SMITH.
